UNITED STATES PATENT OFFICE.

ARTHUR MIDDLETON ROSE, OF YONKERS, NEW YORK, ASSIGNOR TO THE
W. & J. SLOANE, OF NEW YORK.

DESIGN FOR CARPET.

SPECIFICATION forming part of Design No. 25,231, dated March 3, 1896.

Application filed January 31, 1896. Serial No. 577,629. Term of patent 3*1/2* years.

To all whom it may concern:

Be it known that I, ARTHUR MIDDLETON ROSE, a citizen of the United States, and a resident of Yonkers, in the county of Westchester and State of New York, have invented a new and original Design for Carpets, of which the following is a specification.

My design is intended to be used as a border for carpets; and I do hereby declare that the drawing accompanying this specification conveys to any one a clear understanding of the same and is sufficient to enable such person to use my invention.

The design is characterized by a spirally-convoluted bar draped with flower-festoons

and surmounted with spiral and horn forms decorated with flowers and by parallel bands of wicker or cane work with irregular bunches of flowers massed thereon.

What I claim as new, and desire to secure 20 by Letters Patent, is—

The design for carpet, substantially as shown.

In testimony whereof I have signed my name to this specification in the presence of 25 two subscribing witnesses.

ARTHUR MIDDLETON ROSE.
